(57) **CLAIM**

The ornamental design for a carrying pouch for electronic audio systems having headsets, as shown and described.

DESCRIPTION

FIG. 1 is a right-front perspective view of an embodiment of a carrying pouch according to the invention;

FIG. 2 is a right-rear perspective of the carrying pouch according to FIG. 1;

FIG. 3 is a front view of the carrying pouch according to FIG. 1;

FIG. 4 is a rear view of the carrying pouch according to FIG. 1;

FIG. 5 is a left-side view of the carrying pouch according to FIG. 1;

FIG. 6 is a right-side view of the carrying pouch according to FIG. 1;

FIG. 7 is a top view of the carrying pouch according to FIG. 1; and,

FIG. 8 is a bottom view of the carrying pouch according to FIG. 1.
